(57) **CLAIM**

The ornamental design for a recessed luggage fixture, as shown and described.

DESCRIPTION

FIG. 1 is a front perspective view of a recessed luggage fixture;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof; and,

FIG. 8 is a top plan view thereof with environment.

The broken lines showing portions of the handle are for the purposes of illustrating environment and form no part of the claimed design.
